[57] **CLAIM**

I claim the ornamental design for a backpack, as shown and described.

DESCRIPTION

FIG. 1 is a perspective view of a backpack showing my new design;

FIG. 2 is a top plan view thereof;

FIG. 3 is a front elevational view thereof;

FIG. 4 is a right side elevational view thereof, the left side being a mirror image except for the slide fastener pulls; and, FIG. 5 is a rear elevational view thereof.

The broken lines shown throughout the views are intended to represent stitching.
